UNITED STATES PATENT OFFICE

BENJAMIN V. KERSHNER, OF ST. LOUIS, MISSOURI, ASSIGNOR TO UNION SPECIAL MACHINE COMPANY, OF CHICAGO, ILLINOIS, A CORPORATION OF ILLINOIS.

THREAD-CONTROLLER FOR SEWING-MACHINES.

1,203,201.

Specification of Letters Patent.

Patented Oct. 31, 1916.

Application filed January 16, 1914. Serial No. 812,453.

To all whom it may concern:

Be it known that I, BENJAMIN V. KERSHNER, a citizen of the United States, residing at St. Louis, State of Missouri, have invented certain new and useful Improvements in Thread-Controllers for Sewing Machines, of which the following is a description, reference being had to the accompanying drawing and to the figures of reference marked thereon.

The invention relates to new and useful improvements in thread controllers for sewing machines and more especially to a needle thread controller which operates to take up the needle thread after the needle loop is dropped from the looper.

An object of the invention is to provide a thread controller which takes up more or less thread according to the thickness of the material so as to draw the needle loops after they are shed from the looper to substantially the same position relative to the material even though the thickness of the material varies, whereby a uniform tight stitch may be produced.

A further object of the invention is to provide a thread controller of the above type with means for clamping the thread between the take up and the supply at the time the said take up is pulling on the thread to draw up the needle loops.

A further object of the invention is to provide a thread controlling mechanism of the above character with devices whereby the needle on its upward stroke pulls thread from the supply and operates to draw on the needle thread for the final setting of the stitches.

A still further object of the invention is to provide a thread controller of the above type wherein the take up is moved out of contact with the needle thread during the pulling of the thread from the supply and the final setting of the stitches.

These and other objects will in part be obvious and will in part be hereinafter more fully disclosed.

In the drawings which show by way of illustration one embodiment of the invention: Figure 1 is a view partly in section and partly in side elevation showing a sewing machine having my improvements applied thereto. Fig. 2 is an enlarged detail view showing the position of the parts of the thread controlling mechanism when the

needle is at its highest point. Fig. 3 is a view similar to Fig. 2 showing the position of the parts when the needle is at its lowest point. Fig. 4 is a detail showing diagrammatically the position of the parts when the needle loop is shed from the looper. Fig. 5 is a similar view showing the position of the parts when the looper is at the rear end of its stroke and the needle loop is drawn up to the under face of the material. Fig. 6 is a top plan view of my improved thread controlling device. Fig. 7 is a detail in section showing the manner of operating the nippers. Fig. 8 is an end view of the work support with the cover cap removed, illustrating the relative positions of the needles and loopers.

The sewing machine to which my invention is applied is designed particularly for stitching leather and is preferably provided with a plurality of needles arranged in pairs. A threaded looper co-operates with each pair of needles.

In stitching leather, it is desired to form a tight stitch and in order that a tight stitch may be produced, it is essential that the needle loops shall be drawn well up underneath the material. When the thickness in the material varies, some means is necessary for varying the pull on the thread in order that the position of the needle loops relative to the under side of the material may be substantially uniform. If these needle loops are drawn to substantially the same position relative to the fabric on the final setting of the stitches at the upward stroke of the needle, said stitches will be of substantially a uniform degree of tightness.

The invention consists, generally, in providing a take up which engages the needle thread at the time when the needle loop is shed from the looper and draws on the needle thread to take up this needle loop. Co-operating with said take up is a thread guide which is shifted as the thickness of the material varies and the shifting of this thread guide varies the amount of thread drawn up by the take up so that regardless of the thickness of the material said needle loops drawn up by the take up will be uniformly positioned relative to the material. This take up also moves entirely out of contact with the needle thread so as to permit the thread to be drawn substantially straight from the supply with little or no bends.

therein as the needle reaches the upper end and 34 will cause the arm 30 to be lowered. If the thickness of the material decreases,

- ward the arm 23 will also move upward engaging the end of the rod 21 forcing the same inwardly, compressing the spring 22 and releasing the nippers. The nippers are, therefore, closed during the time when the take up arm 45 is pulled on the needle threads and the nippers are released during the time while the take up arm is out of contact with the needle threads.
- 10 On the upward movement of the needles, the thread rolls 46 give up thread to the needles. The amount of thread taken up by the arm 45 is sufficient so as to permit the eyes of the needles to clear the upper face of the material before the needle threads are drawn on by the continued upward movement of the needle bar for the final setting of the stitches. The continued upward movement of the needle bar draws the needle threads against the thread guides 39 and the rollers 44. Pulling on the threads not only sets the stitch but pulls threads from the supply for the next stitch. At this time the nippers are open, the thread rolls 46 on the take up arm 45 are out of contact with the needle threads so that the needle threads are pulled substantially straight from the supply with little or no bends or turns in the thread to place an undue tension thereon.
- 20 The guides 31, carried by the arm 30, are moved up and down according to the varying thickness of the material, as above described. Let us suppose the material decreases in thickness from one stitch to the next, the arm 30 will be thereby raised at its outer end as this decrease in the thickness of the material causes the presser foot to assume a lower position. This decrease in the thickness of the material consumes less needle thread and therefore the take up arm 45 must take up more needle thread in order to draw the needle loop to the same relative position beneath the material. The upward movement of the thread guide 31 varies the distance between said thread guides and the thread rolls 46 when said thread rolls 46 are at the lower end of their stroke. This distance has increased and, therefore, more thread will be taken up and the thread loops properly positioned in the same relation to the under face of the material as the previous loops so that on the final upward movement of the needle, the stitches will be drawn tight.
- 30 If the thickness of the material under the presser foot increases, then the arm 31 will be lowered and less thread will be drawn up by the movement of the take up arm 45. This increase in the thickness of the material consumes more thread and, therefore, the needle loops may be drawn to the same position relative to the under face of the material and the final setting of the stitches will produce stitches of uniform tightness.
- 40 As the needle bar reaches the upper end

of its stroke, thread is drawn from the supply after the final setting of the stitches. By my improved thread controlled mechanism, wherein the needle loops are uniformly positioned relative to the under face of the material regardless of the varying thickness of the material, the needle bar as it reaches the upper end of its stroke will pull off just the right amount of thread for the needles so that a tight stitch can be produced.

While I have described the take up arm as operated to take up the needle threads for drawing up the needle loops, it will be understood that this take up co-operates with the needles themselves in drawing up these loops. In other words, after the needle has passed into the material, the needle thread is doubled upon itself to form the new needle loop and the descent of the needles pull up the needle loops which were previously formed for pulling against the rolls on the take up arm as an abutment and the take up arm also draws up on the needle threads. This variable movement of the take up arm relative to the thread guides 31 causes the pulling up of the needle loops to a uniform degree.

It is obvious that minor changes in the details of construction and the arrangement of the parts may be made without departing from the spirit of the invention as set forth in the appended claims.

Having thus described my invention, what I claim is:—

1. A sewing machine including in combination, an overhanging arm, a shaft mounted in said overhanging arm, a needle bar, a needle carried thereby, means for reciprocating said needle bar from said shaft, a looper co-operating with said needle, thread guides over which the needle thread passes on the way from the supply to the needle and an arm pivotally mounted on said overhanging arm and having a roller at its outer end for engaging the thread between said guiding devices and means for oscillating said arm from said shaft said thread arm being normally out of contact with the needle thread when the needle is at the upper end of its stroke and timed to engage said needle thread substantially as the previous needle loop is shed from the looper for drawing up said previous needle loop.

2. A sewing machine including in combination, an overhanging arm, a shaft mounted in said overhanging arm, a needle bar, a needle carried thereby, means for reciprocating said needle bar from said shaft, a looper co-operating with said needle, thread guides over which the needle thread passes on the way from the supply to the needle and an arm pivotally mounted on said overhanging arm and having a roller at its outer end for engaging the

thread between said guiding devices and means for oscillating said arm from said shaft said thread arm being normally out of contact with the needle thread when the needle is at the upper end of its stroke and timed to engage said needle thread substantially as the previous needle loop is shed from the looper for drawing up said previous needle loop, said needle bar having devices at its upper end for pulling on the needle thread for the final setting of the stitches and for drawing the needle thread from the supply.

3. A sewing machine including in combination, an overhanging arm, a shaft mounted in said overhanging arm, a needle bar, a needle carried thereby, means for reciprocating said needle bar from said shaft, a looper coöperating with said needle, thread guides over which the needle thread passes on the way from the supply to the needle and an arm pivotally mounted on said overhanging arm and having a roller at its outer end for engaging the thread between said guiding devices and means for oscillating said arm from said shaft said thread arm being normally out of contact with the needle thread when the needle is at the upper end of its stroke and timed to engage said needle thread substantially as the previous needle loop is shed from the looper for drawing up said previous needle loop, said needle bar having devices at its upper end for pulling on the needle thread for the final setting of the stitches and for drawing the needle thread from the supply, and thread nippers between said movable thread arm and the supply for clamping the thread when said arm is in engagement therewith and means for releasing the nippers when the needle bar is pulling thread from the supply.

4. A sewing machine including in combination a needle bar, a needle carried thereby, a looper coöperating with said needle, and devices operating to take up the needle thread on the downward movement of the needle whereby the previous needle loop dropped by the looper may be drawn up against the under face of the material, said devices including a movable thread arm which is out of contact with the needle thread when the needle is at the upper end of its stroke, a thread guide coöperating with said movable thread arm, and means for shifting the said thread guiding device according to the varying thicknesses of the material whereby less thread is taken up when the material increases in thickness and more thread is taken up when the material decreases in thickness.

5. A sewing machine including in combination a needle bar, a needle carried thereby, a looper coöperating with said needle, and devices operating to take up the needle

thread on the downward movement of the needle whereby the previous needle loop dropped by the looper may be drawn up against the under face of the material, said devices including a movable thread arm which is out of contact with the needle thread when the needle is at the upper end of its stroke, a thread guide coöperating with said movable thread arm, and means for shifting said thread guiding device according to the varying thicknesses of the material whereby less thread is taken up when the material increases in thickness and more thread is taken up when the material decreases in thickness, said needle bar having devices at its upper end for pulling on the needle thread for the final setting of the stitches and for drawing the needle thread from the supply.

6. A sewing machine including in combination a needle bar, a needle carried thereby, a looper coöperating with said needle, and devices operating to take up the needle thread on the downward movement of the needle whereby the previous needle loop dropped by the looper may be drawn up against the under face of the material, said devices including a movable thread arm which is out of contact with the needle thread when the needle is at the upper end of its stroke, a thread guide coöperating with said movable thread arm, and means for shifting the said thread guiding device according to the varying thicknesses of the material whereby less thread is taken up when the material increases in thickness and more thread is taken up when the material decreases in thickness, thread nippers between said movable thread arm and the supply for clamping the thread when said arm is in engagement therewith, and means for releasing said nippers when the needle bar is pulling thread from the supply.

7. A sewing machine including in combination an overhanging arm, a main shaft mounted in said overhanging arm, a needle bar reciprocating in said arm, a needle carried by said needle bar, a looper coöperating with said needle, a movable thread arm, means operated by said shaft for oscillating said thread arm, thread guides coöperating with said thread arm, nippers located between said thread arm and supply means for normally causing said nippers to grip the thread and means operated by said shaft for opening said nippers, said parts being timed so that said thread arm will pull on the needle thread arm when the nippers are closed and while the needle is moving to the lower end of its stroke, one of said thread guides coöperating with the thread arm being shiftable as the thickness of the material varies whereby the amount of thread taken up by the thread arm is increased when the thickness of the material decreases and is

diminished when the thickness of the material increases.

8. A sewing machine including in combination an overhanging arm, a bracket 5 mounted on said overhanging arm, a shaft located in said bracket, a main shaft mounted in the overhanging arm, devices for oscillating said first named shaft from said main shaft, a thread arm mounted on said first named shaft and normally out of engagement with the needle thread, thread guiding devices coöperating with said arm, a needle bar, a needle carried thereby, a presser bar, a presser foot mounted thereon, 10 a second bracket mounted on said overhanging arm, an arm mounted on said last named bracket and connected to said presser bar whereby the up and down movements of said presser bar will shift said arm, one of 15 said thread guides coöperating with the movable thread arm being mounted on said arm connected to the presser bar.

9. A sewing machine including in combination an overhanging arm, a bracket 25 mounted on said overhanging arm, a shaft located in said bracket, a main shaft mounted in the overhanging arm, devices for oscillating said first named shaft from said

main shaft, a thread arm mounted on said first named shaft and normally out of engagement with the needle thread, thread guiding devices coöperating with said arm, a needle bar, a needle carried thereby, a presser bar, a presser foot mounted thereon, 30 a second bracket mounted on said overhanging arm, an arm mounted on said last named bracket and connected to said presser bar whereby the up and down movements of said presser bar will shift said arm, one of 35 said thread guides coöperating with the movable thread arm being mounted on said arm connected to the presser bar, thread nippers located between the thread arm and supply, means for normally holding said nippers closed, and an arm carried by said 40 first named shaft for releasing said nippers, 45 said parts being so timed that the nippers are closed when said thread arm is drawing on the needle thread.

In testimony whereof, I affix my signature, in the presence of two witnesses.

BENJAMIN V. KERSHNER.
